EMIL SØRENSEN, OF NEW YORK, N. Y., ASSIGNR TO CERTUS PARALLELOMETER COMPANY, INC., A CORPORATION OF NEW YORK.

ANCHOR FOR REMOVABLE BRIDGES FOR TEETH.

1,314,224.

Specification of Letters Patent. Patented Aug. 26, 1919.

Application filed February 17, 1919. Serial No. 277,386.

To all whom it may concern:

Be it known, that I, EMIL SØRENSEN, a citizen of Denmark, and a resident of New York city, in the county of Bronx and State 5 of New York, have invented certain new and useful Improvements in Anchors for Removable Bridges for Teeth, of which the following is a specification.

The object of this invention is to provide 10 a new and improved means for removably anchoring dental bridgework to abutment teeth in the mouth, and particularly to molars and bicuspids, by means of frictional engagement of attachments, with sockets in 15 the abutment teeth.

In describing my new attachment, reference will be had to the accompanying drawing showing the preferred form of my invention, in which all figures are in perspective except Figure 7, which is in plan. Fig. 1 shows the original T form of the bar from 20 which the male portion of the attachment is made; Fig. 2 shows the bar with a portion of the web removed; Fig. 3 shows the finished form of the male portion of the attachment; the flange having been folded back 25 upon itself and away from the web and having been given a curvature, after folding, around a line parallel to the intersection of 30 the flange and the web; Fig. 4 shows the socket which is adapted to fit into the abutment tooth; Fig. 5 shows attachments applied to a bridge carrying two teeth; Fig. 6 shows the abutment teeth with the sockets 35 in place, one tooth being shown in partial section; Fig. 7 shows in plan view the completed bridgework anchored in the abutment teeth which contain the suitably formed sockets.

40 To produce the preferred form of my invention about one-half of the web 1 of a suitable length of a T-shaped bar (Fig. 1) is removed (Fig. 2). To form the anchor the flange is then folded back upon itself at substantially 45 the inner end of the remaining portion of the web, but not into complete contact, the folded portion 2, through the natural resiliency of the metal of which it is made, acting as a spring, to provide frictional engagement between the anchor and the sides of the socket, and the flanges 3 acting as retaining means or members, to prevent primarily a displacement of the abutment teeth. Preferably the flanges and 55 spring are then curved into concentric arcs.

This anchoring device is preferably made of an alloy of platinum and iridium but any other material of suitable strength and elasticity to form the spring may be employed, and the material ought, of course, to be non-corrosive. 60

The spring is preferably formed integral with the anchor. Were the spring soldered to the anchor there would be danger of melting this joint while soldering the anchor to 65 the bridge.

The object in giving the flanges 3 and spring 2 the curvature shown, is to enable enough material to be used to give the requisite strength to the anchor without weakening the tooth by bringing the edges of the flanges too near to the edge of the tooth, or the root of the T too near the pulp chamber of the tooth, as would be the case, if the flanges were in a plane. It will be noted 70 that when it becomes necessary to cut into a sound tooth to make an anchorage for a bridge, the flanges of the T-shaped piece project from either side of the web into the strongest part of the tooth, that is, the 75 enamel while avoiding the pulp chamber in which the nerves are located and which comprises the central portion of the tooth. The bridge to support the artificial teeth may have any suitable shape and is soldered in 80 the usual manner (or may otherwise be suitably attached to) web 4 of the attachment. 85

Socket 6, one of which is intended to be cemented to each abutment tooth, is adapted to receive the anchor 5; the recessed portion 90 thereof being made of such width that the spring 2 and the flange 3 will be forced together and will hold the anchor securely when the same is inserted. The socket 6 is held in the inlay 8, which is secured in the 95 previously prepared opening in the abutment tooth 9.

My invention is obviously not limited to the particular embodiment or arrangement of elements shown and described herein, but the form of its embodiment may be varied within the scope of the appended claims. However, the anchor made in the manner described has all the advantages of an integral structure, and may be manufactured by a 100 minimum number of simple operations. Moreover, the spring member and the flange member, being united at their lower edges, 105 form a structure V-shaped in cross-section; thus enabling the anchor to be readily guided 110

into the socket. This is a feature of great practical importance, in view of the necessity of the frequent removal of the bridge by the wearer for cleaning and sterilizing purposes.

Having described my invention, what I now claim is:

1. A bridge anchoring device comprising a recessed member and an anchor adapted to engage the same, said anchor being formed of a web and flanges arranged in T-shape, and a spring member attached to the flanges, said spring member and flanges together forming a wedge substantially as and for the purpose described.

2. A bridge anchoring device comprising a recessed member and an anchor adapted

to engage the same, said anchor being formed of a web and flanges arranged in T-shape and a spring member attached to the flanges, 20 said flanges and said spring member being disposed in substantially concentric arcs substantially as and for the purpose described.

3. A bridge anchoring device comprising a recessed member and an anchor adapted to engage the same, said anchor being formed of a web, flanges and a spring member all integrally united, the spring member and the flanges being united at their lower edges respectively substantially as and for the purpose described.

In testimony whereof I have hereunto set my hand.

EMIL SØRENSEN.
